UNITED STATES PATENT OFFICE

LOUIS NASSIF, OF WHEELING, WEST VIRGINIA

SHOE POLISHING DEVICE

Application filed April 9, 1932. Serial No. 604,137.

This invention relates to certain new and useful improvements in shoe polishing devices, and more particularly to a device for holding and guiding a strip of fabric while the latter is reciprocated over the surface of the shoe to be polished.

A further object of the invention is to provide a device of the character mentioned providing guiding means for the polishing cloth which completely surrounds the shoe when the latter is placed on the foot plate, thereby affording means whereby the entire surface of the shoe, including the heel portion, may be polished in a convenient manner.

A further object of the invention is to provide a device of simple and inexpensive construction, the same being of a size, shape and weight that it may be carried in the traveling bags of tourists and travelers without inconvenience.

With these and other objects in view, the invention consists in the novel features of construction shown in the accompanying drawing, in which—

Figure 1 is a side elevation of the device with a shoe resting thereon, the polishing cloth being shown in polishing position;

Figure 2 is a top plan view of the device;

Figure 3 is a side elevation of the same; and—

Figure 4 is a section taken on line 4—4, Fig. 3.

Referring to said drawing, the reference numeral 1 designates the front portion of a metal plate, preferably made from cast or stamped aluminum or other suitable lightweight material, the plate in its entirety having a shape in top plan approximating the general contour of the sole of a shoe. Said plate has a heel portion 2 which is separated from the front or toe portion 1 thereof by a raised shoulder 4 formed integrally in said plate, said shoulder keeping the shoe from sliding forward on said plate.

Permanently attached to the shoe plate and completely surrounding the latter is a heavy wire guide 5, said guide being spaced a suitable distance from the side of the foot plate to

form intermediate open spaces 7, and being attached to the plate at the extreme front and rear ends of the latter by means of short rounded supporting members 6, each of which has one end thereof attached to the plate, as 55 by spot welding, and its opposite end attached, also by spot welding, to the guide 5. Each of said guide supporting members 6, as shown in Figs. 1 and 3, is inclined upwardly and outwardly from the foot plate so that 60 the guide 5 is located above the horizontal plane of the foot plate.

In operation, the polishing cloth 8 is placed in a position where it lies transversely across the upper surface of the shoe plate and under the guide 5 at each of the opposite sides of the plate. The user then slips the front portion of his shoe 9 under said cloth and, with his foot resting upon the plate, manually grasps the opposite ends of the cloth and pulls the same alternately upward, this alternate pulling of the ends upwardly resulting in a reciprocating movement of the cloth over the shoe and through the resultant friction imparts 70 the desired polish to the shoe. 75

By reason of the fact that the guide 5 completely surrounds the shoe plate it will be readily understood that the entire surface of the shoe, including the heel portion, may be polished simply by sliding the polishing cloth 80 about the shoe and plate during the polishing operation.

It will also be noted that the cloth-guide 5 projects above the level of the horizontal plane of the plate, thus providing a stop for 85 sliding movements of the foot of the user with respect to the plate.

The supporting members 6, by means of which the cloth-guide 5 is attached to the plate are preferably made round in cross section and are devoid of sharp corners in order to lessen resistance when the sliding polishing cloth comes in contact therewith during the operation of polishing the front and heel 95 portions of the shoe.

The device may be utilized as a combination shoe polisher and body exerciser. In use, the device may be placed on a chair or stool and one foot of the user placed on the device in 100

the manner hereinbefore described. The polishing cloth may be made of such a short length that the user will necessarily be forced to bend forward at his waist in order to grasp the ends of the cloth. During reciprocation of the cloth in the polishing operation a beneficial exercise is thereby imparted to the abdominal and shoulder muscles of the user.

5 What is claimed is—

- 10 In a shoe polishing device comprising a foot plate, guide means for a polishing cloth attached to said plate and spaced away from the sides of the latter, said guide means occupying a position wherein it is elevated above the level of the plane of said plate and completely 15 surrounds the latter, and means located at the opposite ends of said plate for supporting said guide means.

In testimony whereof, I affix my signature.

20 LOUIS NASSIF.
